UNITED STATES PATENT OFFICE.

JOSEPH BARRAJA-FRAUENFELDER, OF BRIDGEPORT, CONNECTICUT, ASSIGNOR TO THE LAKE TORPEDO BOAT COMPANY OF MAINE, OF BRIDGEPORT, CONNECTICUT, A CORPORATION OF MAINE.

SUBMARINE TORPEDO-BOAT.

1,134,940.

Specification of Letters Patent.

Patented Apr. 6, 1915.

Application filed August 12, 1914. Serial No. 856,361.

To all whom it may concern:

Be it known that I, JOSEPH BARRAJA-FRAUENFELDER, a citizen of the United States, residing at Bridgeport, in the county 5 of Fairfield and State of Connecticut, have invented certain new and useful Improvements in Submarine Torpedo-Boats, of which the following is a specification.

Heretofore, the use of steam engines in 10 submarine torpedo boats for supplying the necessary power for surface operations has been impracticable, owing to the intense heat emitted from the boilers, and as no prevention has heretofore been made for 15 preventing the heat from being distributed throughout the boat, it will be readily apparent that the use of steam power has been impracticable since the intense heat of the boilers, prevents the closing of the hatches 20 and ventilators for a considerable time, after the fire has been extinguished, hence preventing the submergence of the boat upon short notice which is the essential requirement of all submarine torpedo boats.

25 The object of the invention is to provide a boiler room in submarine torpedo boats which may be completely cut off from the living and working quarters of the boat, whereby the heat emitted from the boilers 30 and from the boiler room may be prevented from being distributed throughout the said living and working quarters when the boat is submerged, thus making it practical to use steam engines for operating the boat on 35 the surface instead of the present oil engines, so that greater power and consequently higher surface speeds may be obtained than has heretofore been possible in this class of vessels.

40 The invention consists in dividing the main hull by suitably spaced transverse partitions or bulk-heads, providing a water compartment within the main hull of the boat, and in arranging a closed chamber 45 within the said compartment providing a boiler room, said chamber being of smaller dimensions than the water compartment whereby a water-jacket space is provided around the said chamber which is adapted to 50 be filled with water from the water of flotation, said chamber communicating with the opposite ends of the boat through passageways which are designed to be closed at each end, whereby to provide air-locks to prevent

the heat of the boiler room from escaping 55 into the boat when the latter is submerged, means being provided for ventilating the boiler room, and for supplying forced draft to the boilers, and means also provided for causing a circulation of water through the 60 water-jacket. These and other features germane thereto constitute the invention, as will be hereinafter fully described and then pointed out in the claims.

65 In the accompanying drawings, illustrating the invention, Figure 1 is a diagrammatic side elevation of a submarine torpedo boat illustrating the construction and preferred location of my invention, the boilers and their connections being omitted for the 70 purpose of clearly illustrating the construction of the boiler room. Fig. 2 is a diagrammatic vertical longitudinal section drawn through the boiler room and the adjacent section of the hull of the boat. 75 Fig. 3 is a horizontal section drawn on the line a—a of Fig. 2. Fig. 4 is a vertical transverse section drawn on the line b—b of Fig. 2 looking in the direction indicated by the arrows. Fig. 5 is a diagrammatic horizontal section illustrating a slight modification of the invention.

80 1 designates the hull of a submarine or submersible torpedo boat of any improved design or form of outer hull, within which, 85 preferably forward of amidships, are transverse partitions or bulk-heads 2 and 3 which are preferably riveted to the ribs 1' of the hull air- and water-tight to provide a water holding compartment 4. Within the compartment 4 is a closed, preferably cylindrical chamber 5, of less diameter and length than the said compartment, and which is constructed of shell plating 6 and a series of external ribs or frames 7, the whole being of sufficient strength to withstand the pressure incident to submergence. The chamber 5 is held in position within the compartment 4 by suitable frames 8 (Fig. 4) preferably riveted to the ribs 1' of the main hull and to the 90 ribs or frames 7 of said chamber. The space thus formed between the hull of the boat and the chamber 5 provides a water-jacket, water being admitted to said jacket from the surrounding body of water through an opening in the plating of the hull 1 and controlled by a valve 9 the stem 10 of which extends upwardly into the boiler room and is 95 100 105

provided with a hand wheel 10' as shown. The ends 5' of the chamber are provided with openings 11 which are located opposite opening 12 formed in the adjacent transverse partitions or bulk-heads 2 and 3, and within each pair of adjacent openings is fitted a frame 13 providing passages or doorways leading into the boiler-room. The frames are connected air- and water-tight to the ends 5' of the chamber 5 and to their respective adjacent bulk-heads 2 and 3, the ends of each frame being extended through their openings 11 and 12 and provide seats for doors 14 which are hinged adjacent to one side of the frames in suitable manner and control the passages through the said frames. When the doors are closed and locked the passages form air-locks to prevent the escape of the heat from the boiler room into the living and working quarters of the boat as will be hereinafter further described. Any suitable means commonly used for locking doors and hatches in submarine boats may be employed for locking the doors 14 in closed position.

Within the chamber 5 is arranged a horizontal partition or floor 15 the space above which provides a boiler-room 16 in which is located preferably four steam boilers or generators 17 which may be of coal or oil burning types and of any suitable design. The smoke-stacks 17' of the boilers open through the top of the chamber 5 into an exhaust manifold 18 built upon and connected air- and water-tight to the top of the said chamber and extending through an opening formed in the plating of the hull 1, said manifold being also connected to the plating of the hull 1 air- and water-tight by means of suitable angle frames. The top of the manifold terminates in a short pipe section 18' and is provided with a cover 19 designed to be closed and locked upon the top of said pipe section air- and water-tight when the boat is submerged. As shown in dotted lines in Fig. 2 the pipe section 18' may be fitted with an extension 20 which may be either a single removable pipe or smoke-stack or a telescopic smoke-stack designed to be withdrawn into the manifold 18 when the cover 19 is to be closed. The smoke-stacks 17' extend slightly above the plating of the chamber 5 and are provided with annular flanges which are riveted to the plating of said chamber, and their upper ends are provided with covers 21 which are designed to be locked upon the tops of the said smoke-stacks air- and water-tight to prevent ingress of water to the boiler tubes in the event of water leaking into the manifold. Any suitable means (not shown) may be employed for opening and closing the covers 21 from within the boiler room. The manifold is constructed with a double wall, the space between the walls pro-

viding an air-jacket, and the said smoke-stacks 17' are surrounded by sleeves 17" providing air-jackets which open into the manifold 18, the purpose of the jackets being to prevent the heat radiating from said stacks from entering the boiler room. Water is supplied to the boilers through pipes 22 extending from fresh water-tanks (not shown) built in the boat, and steam is conducted from the boilers to suitable engines 75 (not shown) through pipes 23.

As shown in Fig. 4, the smoke-stacks 17' of the boilers open into the manifold which is arranged exteriorly of the chamber 5 while in Fig. 5 the manifold 81 is connected direct to the smoke chambers of the boilers and is arranged entirely within the chamber 5 and from the manifold 81 extends a single smoke-stack 82 which is extended up through an opening in the top of the chamber 5 and through an opening in the plating of the hull 1 in suitable manner. It will, of course, be understood that the smoke-stack 82 will be provided with a cover similar to the pipe section 18' of the manifold 18.

With the use of coal burning boilers, air is forced into the ash-pits of the boilers through pipes 25 provided with branches 25' which open through the bottom of the ash-pits. The pipes 25 extend from suitable blowers 26 mounted within boiler room and connected to one end of the shafts of suitable motors 27, the inlets to said blowers being connected by pipes 28 which extend through openings formed in the plating of the chamber 5 and through openings in the plating of the hull 1 and have their upper ends designed to receive removable hoods 28'. To ventilate the boiler room I provide suction blowers 29 which are connected through clutches 30 with the opposite ends of the shafts of the motors 27 and to the outlets of said suction blowers are connected pipes 31 which also extend through the plating of the chamber 5 and the plating of the hull 1 and are provided with removable exhaust pipes 32 which, like the inlet pipes 28', are extended upwardly a suitable distance above the main hull or deck of the boat. Valves (not shown) control the passage through the pipes 28 and 31 and are operated by hand wheels 33 Figs. 2 and 4. The admission of air to the ash-pits of the boilers is controlled by valves 34 arranged in the pipes 25 to fold or seat over the inlets to the branches 25'. With the use of oil burners where forced draft into the ash-pits of the boilers is unnecessary, the valves 34 are closed so that the air passing through the pipes 25 will be permitted to escape through the ends of said pipes into compartments (hereinafter described), formed below the horizontal partition 15 of the boiler room, the air being permitted to escape from the compartments into the boiler 130

room through slots 15' formed in the said horizontal partition 15 in front of the boilers 17. With the use of oil burners the necessary draft and the hot air in the boiler room will be drawn into the fire-boxes through the doors opening into the same and carried off, with the fumes from the burning oil, through the smoke-stacks 17. Also with the use of oil burners, it may be stated, the clutches 30 are adjusted to throw the suction blowers 29 out of operation so that the hot air in the boiler room will be carried off through the fire-boxes of the boilers.

15 The horizontal partition is centrally supported by parallel longitudinal girders 35 (Fig. 4), having their longitudinal edges connected air- and water-tight to the partition 15 and to the plating 6 of the chamber 5, respectively, and their ends connected air- and water-tight to the ends of the chamber 5. In the compartments thus formed between the girders 35 and the sides of the chamber 5, are series of transversely arranged supporting frames 36 for the partition 15, and located between the said girders is an inverted U-shape trough 37 (Fig. 4), having its lower longitudinal edges connected air- and water-tight to the plating of the chamber 5, and its ends extended through the ends 5' of the chamber and connected air- and water-tight to the transverse partitions 2 and 3 and surrounding openings therein. The longitudinal edges of the trough 37, between the ends of the said chamber and the transverse partitions 2 and 3 are closed by suitable plates, and it will be understood that the said plates, as well as the sides and the top of the trough 40 37 are connected air- and water-tight to the ends of the chamber to prevent water entering said chamber when admitted to the water-jacket. The space thus formed by the trough provides a passage-way between the forward and after ends of the boat when the doors controlling the passages into the boiler room are closed. The space around the trough 37 provides a water-jacket into which water is admitted from the compartment 4 through openings 38 (Fig. 4), formed in the plating 6 of the chamber 5. Suitable valve controlled vents (not shown) will, of course, be provided for venting the compartment 4 and the water-jacket around the trough 37.

When the boat is operating on the surface, water is admitted to the compartment 4 around the chamber 5, to the water of flotation, and when the boat is submerged the said compartment is completely filled so that it not only provides a water-jacket entirely around the chamber 5, but also then serves as a ballast-tank. In order to create a circulation of water within the compartment or water-jacket I arrange a pipe 39

within said compartment at each side of the chamber 5, and extend the rear ends of said pipes through the after transverse partition or bulk-head 3 and connect them to suitable water circulating pumps 40 which have their outlets connected by short pipes 41 which open through the plating of the hull 1, to the surrounding body of water. The pumps 40 are operated by motors 42. The pipes 39 are open at their free ends and are provided with inlets throughout their length so as to withdraw the water from the compartment throughout its entire length. When the water circulating pumps are in motion, it will be understood that the sea-valve 9 is also open so that water is permitted to enter the compartment as it is withdrawn therefrom and pumped overboard, thus maintaining a constant circulation of water through the water-jacket which consequently keeps down the temperature in the boiler-room in the same manner as with all explosive engines.

In Fig. 5, I illustrate a slightly different method of causing a circulation of water through the water-jacket or compartment around the chamber 5. In this construction the plating of the hull 1 is provided with openings 50 leading into the water-jacket or compartment which are surrounded by hoods 51 having gate valves 52 controlling the inlets to and the outlets through said hoods. The valves 52 are located within the hoods and the latter are also provided with outwardly opening gate valves 54 which are hinged to the outer faces of the hoods, the said valves 54 of the forward hoods being hinged to the rear ends thereof to thus serve, when open and the boat is under way, to direct water into the hoods and into the water-jacket, while the valves 54 of the hoods at the after end of said water-jacket are hinged to the forward ends of their hoods and thus serve, when open, as shields to permit the water to freely escape from said water-jacket.

When operating on the surface of the water under steam power the air pumps or fans are set in motion as previously described, and as the doors of the boiler room and the hatches leading into the main hull of the boat are open it will be apparent that the boiler room as well as the working and living quarters of the boat are kept cool and supplied with fresh air so that no serious difficulties are presented in operating the boat under steam power. However, as submarine torpedo boats are required to be sealed and made ready for submergence at short notice and in a comparatively short space of time, it will be appreciated that unless some provision were made for preventing the heat emitted from the boilers from entering the living and working compartments of the boat, that it would be

physically impossible for the occupants to remain in the boat with the hatches and ventilators closed for even short periods of time. With my construction of the boiler-room, however, when the boat is to be submerged the fires are first extinguished, the valves controlling the passage through the various pipes are then closed and the doors 14 then closed and sealed so that the heat 5 from the boilers is confined to the boiler-room proper, thus permitting the submergence of the boat and the necessary submerged operations to be carried out without the difficulties and inconveniences heretofore 10 experienced with the use of steam power in submarine vessels.

While I have shown my invention as installed in a single hull submarine boat I do not wish to be understood as limiting myself 20 to this design of boats, as it will be appreciated that the invention may be carried out in boats of double hull construction. In this application of my invention the transverse partitions or bulk-heads 2 and 3 would, 25 of course, be connected to the inner hull of the boat and suitable openings provided in the inner hull to afford communication between the water space between the hull sections and the water-jacket spaces at the ends 30 of the chamber 5. As this construction will be obvious to any one skilled in the art to which the invention relates, I have not thought it necessary to illustrate the same. While not shown it will also be obvious that 35 the usual means employed for expelling the water from the ballast tanks of this class of boats will also be used to pump all of the water from the compartment 4 should it be desired to do so.

40 What I claim is:—

1. A submarine torpedo boat, having transverse partitions therein providing a water compartment, a valve-controlled opening leading into the compartment from the 45 surrounding body of water, a chamber providing a boiler room located within said compartment and communicating with the interior of the boat, and means for causing a circulation of water in said compartment.

50 2. A submarine torpedo boat, having transverse partitions in the main hull providing a water compartment, a valve-controlled opening in the main hull leading into said compartment from the surrounding 55 body of water, a chamber of less diameter than the boat arranged within said compartment and communicating with the interior of the boat, said chamber providing a boiler-room, doors controlling the passage 60 through the communications, means for circulating water through said water compartment, and means for ventilating said boiler-room:

65 3. A submarine torpedo boat, having transverse partitions in the main hull pro-

viding a water compartment which opens to the surrounding body of water, a valve controlling the opening leading into the compartment, a chamber located within said compartment providing a boiler-room, said 70 chamber being of less diameter than the hull and of less length than said compartment whereby to provide a water holding space around and at the ends of said chamber, passage-ways leading into said chamber 75 through said partitions, a door for closing each end of each passage-way whereby to provide air-locks for the purpose specified, means for causing circulation of water through said compartment, means to supply 80 fresh air and means to ventilate said boiler-room.

4. A submarine torpedo boat, having a chamber providing a boiler-room arranged within the main hull and surrounded by a 85 water-jacket, said water-jacket communicating with the surrounding body of water, means for controlling the admission of water to said water-jacket and means for causing a circulation of water through said 90 water-jacket.

5. A submarine torpedo boat, having transverse partitions arranged in the main hull providing a water compartment which 95 opens to the surrounding body of water, a valve controlling the opening, a chamber providing a boiler-room arranged in said compartment and communicating with the interior of the boat, doors controlling the 100 communications, boilers arranged in said 100 boiler-room, smoke-stacks leading from said boilers, a manifold extending from said chamber and opening through the hull of the boat and into which said smoke-stacks extend, a cover for the outlet from 105 said manifold, covers for said smoke-stacks, means to supply fresh air to the fire boxes of the boilers and to said boiler-room, and means for carrying off the warm air from 110 said boiler-room.

6. A submarine torpedo boat having partitions arranged in the main hull providing a water compartment which opens to the surrounding body of water through the hull plating of the boat, a valve controlling said 115 opening, a chamber arranged within said compartment providing a boiler-room which communicates with the ends of the boat, doors controlling said communications, a horizontal partition or floor arranged in said chamber, a passage-way arranged under said horizontal partition or floor and opening through the ends of said chamber and through said bulk-heads whereby to afford a passageway between 120 the ends of the boat when said doors leading into the boiler-room are closed.

7. A submarine torpedo boat having transverse partitions arranged in the main hull providing a water compartment which 125

- opens to the surrounding body of water, a valve controlling said opening, a chamber providing a boiler-room located within said water compartment and spaced from the hull of the boat and from said transverse partitions whereby to provide water-jackets around and at the ends of said chamber, passage-ways leading into the ends of the boiler-room through said transverse partitions, doors arranged at each end of the passage-ways, a horizontal partition or floor arranged in said boiler-room, steam boilers mounted on said horizontal partition or floor, smoke-stacks extending from said boilers through the top of said chamber, covers for said smoke-stacks, a manifold opening through the main hull and into which said smoke-stacks extend, a cover for the outlet from said manifold, means to supply forced draft to the fire boxes of said boilers and fresh air to the boiler-room, means for carrying off the warm air from said boiler-room, and means for causing circulation of water through said water-jacket.
8. A submarine torpedo boat, having transverse partitions in the main hull providing a water compartment, a chamber providing a boiler-room located within said compartment and communicating with the interior of the boat, said chamber being spaced from the hull of the boat, and from said transverse partitions whereby to provide a water-jacket around and at the ends of said chamber, a valve-controlled opening leading into said water-jacket from the surrounding body of water, a suction pipe extending into said water-jacket, and a circulation pump connected to said pipe having its discharge opening into the surrounding body of water.
9. A submarine torpedo boat, having transverse partitions in the main hull providing a water compartment, a valve-controlled opening leading into the compartment from the water of flotation, a chamber arranged within said compartment and communicating with the ends of the boat, said chamber providing a boiler-room, steam boilers arranged in said boiler-room having smoke-stacks opening into a manifold, said manifold opening through the hull of the boat, covers for said smoke-stacks, and a cover for the outlet from said manifold, means to supply forced draft to the fire boxes of the boilers and fresh air to said boiler-room, and means for drawing off the warm air from said boiler-room.
10. A submarine torpedo boat, having a compartment built within the main hull between its ends and thereby providing a boiler-room communicating with the interior of the boat, a water-jacket arranged around and at the ends of said boiler-room, said water-jacket serving as a ballast space when the boat is submerged, means for controlling the admission of water to said water-jacket, and means for controlling the communication between said boiler-room and the interior of the boat.

In testimony whereof I have hereunto set my hand this 7th day of August, A. D. 1914.

JOSEPH BARRAJA-FRAUENFELDER.
